BATTERY TERMINAL CLAMP AND CABLE CONNECTER

John A. Kimball, Taylorville, Ill.

Application March 12, 1934, Serial No. 715,073

3 Claims. (Cl. 173—259)

This invention relates to battery terminal clamps and connectors for use in connecting the ends of battery cables to the terminal posts of storage batteries. Ordinarily screw or bolt operated clamps of various kinds are employed for this purpose, but such clamps readily corrode and become rusted to their seats so that they are then hard to loosen or remove without danger of damage to the battery and plates thereof.

Moreover such corrosion penetrates the joints of the connection and destroys or seriously impairs the electrical action.

It is the prime purpose of the present invention to provide a terminal clamp and connector which is resiliently held to its seat upon the post, and which therefore may be readily and quickly installed or removed by simply prying the same on or off through the use of a screw driver or similar bitted tool, or with the hands alone.

Another object is to provide a terminal clamp and connector comprising a connector lug and contact element in unitary form, the same being adapted at one portion for engaging the end of a cable and at another portion for contacting a terminal post, and means for resiliently pressing the two together for maintaining the electrical connection.

Still another object is to provide a terminal clamp and connector comprising a connector lug or element adapted for engaging an end of a cable and for contacting one side of a terminal post, and means having a bearing at the opposite side of the terminal post for resiliently pressing the connector lug to the post for maintaining the electrical connection.

And still another object is to provide in a device of the kind referred to, the combination with a battery terminal post and a cable end, of an electrical connector lug adapted at one portion for contacting one side of the terminal post and provided with means for engaging the cable end, and a resilient or spring link or yoke connected at one portion with said connector lug, the opposite portion of the link having a bearing at the opposite side of the terminal post for resiliently pressing the connector lug to the post for maintaining it in place thereupon, the said bearing point of the yoke being provided with a pry aperture or space for the insertion of an operating tool for installing or removing the said device.

Another object is to provide a terminal device of this kind embodying a connector lug adapted for connection to the cable and for contacting one side of the terminal post, a contact element adapted for engaging the other side of the post

and a resilient yoke connecting the elements to draw them together on the post, the said contact element having notches to clear the upper end of the post as the device is applied thereto and there being provided an adapter and protecting element over the post both to increase the size of a small post to fit the device, and to protect the post from scoring and marring by the device as it is applied and removed.

With these and such other and further objects and advantages in view as will appear from the following specification taken in connection with the accompanying drawing wherein are shown several preferred embodiments of the invention, attention is now directed to the said drawing, 15

Figure 1 is a side elevation of one preferred form of the invention, the device being here shown as in process of application to and upon a battery terminal post, the screw driver here shown as an operating tool being moved for the purpose as represented by the arrow.

Figure 2 is a view similar to that of Figure 1, showing the device or clamp as in the process of removal from the terminal post, the screw driver being moved for this purpose as indicated by the arrow.

Figure 3 is an enlarged plan view of the specific form of clamp and connector shown in Figures 1 and 2.

Figure 4 is a side elevation of the structure of Figure 3, showing the action of the clearance notches in the contact lug.

Figure 5 is a side elevation of a modified form of clamp and connector as mounted on a terminal post.

Figure 6 is a plan view of the assembly shown in Figure 5.

Figure 7 is a side elevation of still another modification of the invention showing the use of an adapter and protecting element for the terminal post and the action of the screw driver bit in applying this form of connector to the post.

Figure 8 is a plan view of the adapter and protecting element as mounted on the post.

Figure 9 is a detail view of one side of a terminal post showing the effect thereon of the use of this invention in the way of automatically scraping the contacting surfaces of the post to afford a good electrical connection.

As shown in Figures 1 to 4 the invention comprises a connector lug and contact element 1, the same being formed at one portion with a sleeve 2 into which a cable end 3 may be readily inserted and soldered in usual manner for a good elec-

trical connection, the said lug being cut away semi-circularly at one margin to form a curved contact face 4 well adapted for closely positioning against one side of a battery terminal post 5. 5 The element 1 is formed laterally and medially with the oppositely positioned yoke sockets 6 opening out alongside the sleeve 3 and away from the post engaging end of the lug as shown at 6a. A resilient connecting loop, yoke or link 7 is provided, 10 the same being made preferably of spring metal, such as a suitable length of spring wire of proper gage, this length of wire being bent medially upon itself to form a general bight portion 8 and spaced and parallel legs 9, the ends of 15 the legs being bent straight down toward the lug 1 at 10, and the extremities 11 of the legs being then turned inwardly in transverse alignment and freely seated within the sockets 6 of the lug, the general bight portion 8 of the yoke being turned first downwardly or so as to lie adjacent 20 the terminal post when mounted, and out of the plane of the legs 9, as represented at 12.

A contact lug 13 of U-shaped form is provided and has notches 14 to receive the bight 8 of the 25 yoke 7 whereon the lug is mounted and held by hammering down small teats or ears 15 overhanging the notches 14 as shown. So mounted, the ends of the legs or sides 16 of the lug 13 may be turned inwardly toward the connector element 1 as shown throughout the drawing.

In the use of this form of the invention the cable end 3 is first properly inserted and soldered in the sleeve 2 and the lug 1 is seated against one side of the terminal post 5 with the contact 35 face 4 properly adjusted to the post. The yoke 7 and contact lug 13 are then lowered over against the post as shown in Figure 4 and the bit 17 of a screw driver 18 or similar tool is placed between the bight 8 and the side of the post oppositely to the lug 1 as represented in Figure 1. The handle of the screw driver being then pulled back as indicated by the arrow, the yoke 7 is readily sprung and the contact lug 13 moved down over the top of and against the side of the post after 40 which the tool is removed. The reverse of this operation removes the device from the post as shown in Figure 2. It will be noted that the length of the yoke 7 is such that the bight 8 is spaced from the post 5 sufficiently to provide a 45 tool space or opening 19 for the reception of the screw driver bit 17 as described. In the applied position of the device the edges of the contact lug sides 16 engage and score the post 5 as shown at 50 forming a clean and low resistance electrical connection. Also in the process of working 55 the contact lug 13 down over the post the end of the screw driver bit 17 will bite into the soft lead of the terminal post 5 obtaining a good grip for the necessary prying action and forming 60 what might be termed a "ratchet action", the steps or bites formed by the tool in the post being indicated at 21 in Figure 9. The edges of the 65 said contact lug sides 16 may have clearance notches 22 which clear the upper end or corner of the post 5 as the device is being applied facilitating the operation. The sockets 6 for the yoke 7, opening as they do out alongside the sleeve 2, the yoke 7 may be readily removed from the connector lug when the device is not in use and then 70 by placing the yoke in a vise it may be drawn up and adjusted to any size and to grip the post tightly when the device is applied. This arrangement also makes for convenient replacement of any of the elements if necessary.

75 In the embodiment of the invention shown in

Figures 5 and 6 the connector lug 1a has the sleeve 2a positioned or extended crosswise of the lug along the end remote from the post 5a and the yoke 7a is here shown as being in the form of a regular C-shaped loop with the extremities 11a brought around into transverse alignment and pivotally seated in the sockets 6b, the bight portion 8a of the loop being connected to the contact lug 13a exactly as described above. The 10 operation of this form is similar to that fully described hereinbefore.

As shown in Figures 7 and 8 an adapter and protecting element 23 may be used, the same comprising an arcuate apron-like portion 24 adapted to fit over the side of the terminal post 15 5b and a supporting lip or finger 25 adapted to overlie the top of the post. When so mounted the contact lug 13b may be forced down over this apron portion 24 of the adapter and pressed thereagainst by the action of the yoke 7b and the 20 connector lug 1b. This adapter not only increases the size of a very small post so as to permit the use of the clamp thereon but also protects the post from the scoring action of the lug 13b and of the screw driver bit 17b as will be readily evident. The said bit 17b will, of course, engage the apron 24 and act as a pry to work the contact lug down over the post in the manner described and as shown in Figure 7. These adapters may be made up in various sizes and thicknesses for 30 various terminal posts and to compensate for wear and stretching of the lugs and the yoke.

It is thought that the formation, structure, 35 operation and advantages of the invention will be fully understood from the foregoing descriptions. Some of those advantages are: that the pivotal mounting of the resilient yokes to their contact lugs render those lugs self-adjustable to the sides of the terminal posts upon which they are used; that these devices may be easily and 40 readily applied or removed and cannot become sealed to the posts through corrosion to the extent that they are hard to remove; that the 45 slideable or frictional contact of the lugs upon the sides of the posts in the act of mounting same operates automatically to scrape off any insulating films of grease, dirt or rust that may have accumulated, thereby providing at all times a perfect electrical contact and connection; and that the resiliency of the yokes render them self 50 adjusting to different sizes of posts.

The effect of the frictional and slideable contact of the contact lugs or bearing points of the devices, upon the side surfaces of the terminal posts, is clearly shown in Figure 5 of the drawing, where is shown also the bit marks formed by the operating tool into the comparatively soft metal of the post, whereby the tool is enabled 55 easily to act as a pry in manner pointed out.

And while I have here pointed out and described certain specific forms of the said invention, and the several structural details thereof, it is understood that I may vary those forms and details as may be desirable or necessary in the practical development of the invention for commercial purposes, not departing, however, from the spirit of the invention as defined in the appended claims.

I claim:

1. In a device of the kind described, a connector 70 lug for removably contacting one side of a battery terminal post, the said lug having a sleeve for receiving a battery cable end and having sockets opening out alongside the sleeve, a contractile spring yoke having its ends seated in the 75

said sockets and including a bight, a U-shaped contact lug mounted on the bight of the yoke and adapted at its sides to engage the opposite side of the terminal post to hold the said connector lug in place thereon, the said sides of the contact lug having notches to clear the top of the terminal post as the lug is forced down over the post.

2. In a device of the kind described, a connector lug formed for removably contacting one side of a battery terminal post, means on the lug for engaging a cable end, a contractile spring yoke connected at one portion with the said lug and including a bight portion disposable at the opposite side of the terminal post, and a contact lug pivotally mounted upon the said bight of the yoke, the said contact lug being notched out

at its side adapted for contacting the terminal post to facilitate its clearing the top of said post as it is forced down over the same.

3. In a device of the kind described, a connector element for removably contacting one side of a battery terminal post, means on the element for engaging a cable end, a contractile spring yoke pivotally connected with the connector element and including a bight portion disposable at the opposite side of the terminal post, and a contact element pivotally mounted on the bight portion, the contact element being formed for setting at the said opposite side of the terminal post and recessed to facilitate its clearing of the top of the post as it is forced down over the same.
